WILLIAM B. LODGE, OF DANBURY, CONNECTICUT.

Letters Patent No. 66,095, dated June 25, 1867.

IMPROVEMENTS IN FULLING-STOCKS.

The Schedule referred to in these Letters Patent and making part of the same.

TO ALL WHOM IT MAY CONCERN:

Be it known that I, WILLIAM B. LODGE, of Danbury, in the county of Fairfield, and State of Connecticut, have invented a certain new and useful Improvement on Fulling-Stocks, of which the following is a full, clear, and exact description, reference being had to the accompanying drawing, forming part of this specification, and in which—

Figure 1 represents a side elevation of a fulling-mill, constructed according to my improvement.

Figure 2, a longitudinal section thereof; and

Figure 3 a plan of the same.

Like letters indicate corresponding parts throughout the several figures.

The nature of my invention consists, firstly, in a novel mode of raising the hammers or beaters by a smooth cam or friction motion in the place of the ordinary toe and wiper action, and whereby friction is reduced; also in regulating the fall of the beaters, by means of a spring or springs made adjustable as regards their tension to control the force of the blow; likewise said invention further consists in a hollow box-like formation on the outside or surrounding the bed and bosom of the mill, and supplied with water heated by steam or otherwise; also in an open-work or perforated bosom, for the circulation of the heated water through the same, and in constructing the bosom of a series of rollers that assists in turning the goods, and admit of a more rapid motion being given to the stocks; said invention also embracing India-rubber or other like soft and elastic toes to the beaters, to prevent injury to the goods being fulled or felted.

Referring to the accompanying drawings, A represents the standards and framework of the mill; B, the swinging beaters or hammers, hung or pivoted as at *a*, for operation as in other fulling-stocks, but differing therefrom in the following respects: Instead of lifting the beaters by the ordinary toe and wiper action, which induces much wear and friction, I cause said beaters or hammers to be raised by means of revolving cams, or smooth friction-blocks C, cut away substantially as represented in fig. 2, so as to lift during a portion of their revolution, and suddenly let drop the hammers after being raised, said cams thus operating in a smooth and easy manner, on, say, the backs of shoes *b*, fast to the hammers, and being, it may be, rotated by gear *b* *c*, on horizontal shafts D E, the latter of which carries the cams. A further difference also is to be found in means for controlling the force of the blow, consisting of a spring or springs, F, arranged within and acting on drums *d*, that carry straps *e*, fast at their one end to said drums, and at their others to the hammers, the fall of which, or force of blow, they serve to regulate to suit different kinds or qualities of work, accordingly as more or less tension is given to the springs, by, say, an endless screw, *f*, working into a worm-wheel, *g*, fast on the shaft that carries the drums; such means, however, may be materially varied to produce the same action or effect in substantially like manner. Likewise, instead of the toes G of the hammer being made as usual of wood or other like hard material, I preferably construct them of India rubber, gutta percha, or other analogous pliable and elastic substance, which prevents cutting of or injury to the goods undergoing the process of felting or fulling. H is the bed of the stocks, which, with the bosom I, is arranged within a hot-water box, J, supplied in any suitable manner, and heated by steam or otherwise, the same materially assisting and improving the fulling of the goods. To yet further improve, however, the cleansing and fulling or felting of the work, I make the bosom I of a perforated or open-work character, to allow of the circulation of hot water from the box J amongst the goods, and which perforated or other open-work construction of the bosom is or may be preferably given it by forming said bosom of a series of rollers, *s*, that not only allow of the passage of the water in between or through them, but enable the goods, in being beaten by the hammers, to turn more freely, and so render more uniform and thorough the fulling of a number of goods worked in mass, besides rendering a more rapid action of the beaters feasible.

Fulling-stocks thus constructed may be so fitted as to be both portable and durable, and will accomplish more work in a given time than the ordinary stocks.

What I claim as my invention, and desire to secure by Letters Patent, is—

1. The combination, with the hammers or beaters B, of the cam or friction-blocks C, operating to effect the lift of the former, and to suddenly release them when raised, substantially as specified.
2. The combination, with the hammer or hammers of the mill, of an adjustable spring tension device, arranged to control their fall, essentially as herein set forth.
3. The combination of the toes G, made of India rubber or other analogous soft material, with the hammers B, substantially as specified.
4. The combination with the beater B of the hot-water box or bath J, and the bed and bosom H I, operating on the material being fulled substantially as specified.
